MACHINE FOR SETTING PROJECTILE FUSES

Anton Gietmann, Dusseldorf, Germany, assignor
to Rheinische Metallwaren- und Maschinen-
fabrik, Dusseldorf-Derendorf, Germany, a cor-
poration of Germany

Application December 26, 1933, Serial No. 704,043
In Germany January 11, 1933

4 Claims. (Cl. 86—23)

With modern automatic fuse setting machines having two rotatable setting members independent of each other, for the timing process one setting member, generally the lower one, is temporarily coupled with a rotating driving device, and is thereby set temporarily in operation. This connection is initiated by a projectile being inserted in the setting socket and effected by means of coupling members, for example a coupling disc 5 adapted to turn on a quick-pitch screw thread. The coupling is disengaged by means of bolt members which engage in the lower setting member after the necessary timing rotation, which members, also, by releasing an optical or 10 acoustic signal device, immediately signal the completion of the timing, and, if necessary, at the same time actuate a locking device for preventing axial movement of the projectile in the setting socket.

20 In a known arrangement for obtaining such a signal, the control of a visual signal is made dependent on the up and down movement of the bolting device for locking the lower setting member when the timing operation is completed. In 25 this case the signal indicating the completion of the timing is made when the bolting device reaches its highest position. On the downward movement of the latter no matter to what extent, the signal disappears and again reappears 30 when the bolting device reaches its highest position corresponding to the locked position of the setting member. False timing indications are given when the projectile, on being inserted, does not sink into the setting socket as far as the 35 lower position in the setting socket in which position occurs the engagement of the spring pressed setting lugs or noses in the appropriate notches in the projectile and fuse. In such a case the setting noses are not pressed sufficiently far outwards by the sinking projectile. These lugs are located close to the periphery of the projectile a little below the respective notches intended to receive them, and prevent the projectile from sinking into the position necessary for the time 40 setting of the fuse. Then, although the weight of the inserted projectile effects the release for rotation of the setting member and the engagement of the coupling device, the fact that the setting lugs have not been projected sufficiently 45 allows a partial and immediate upward movement of the nose-securing ring which is initially depressed by the inserted projectile. The bolting device thereby is released for engaging in the lower socket member directly at the beginning of the setting operation and springs into 50

the appropriate notch, no matter whether the setting lugs have been able or not to engage at all during the first and in this case only revolution. In such a case this signal device then indicates a completed timing operation although the fuse of the projectile has not been set or has been incorrectly set.

5 In contrast with the above, in the automatic fuse setting machine according to the present invention a signal device is actuated in dependence on the depth of insertion of the projectile in the setting socket, the signal being given either when the machine is empty and ceasing when the projectile reaches a depth in the setting socket which ensures correct operation of the timing 10 means, or which is given only when the projectile has reached the correct depth and does not occur at other times.

15 For this purpose, there is inserted in the control device of the signal a locking device which, according to the depth of the projectile in the setting socket, is either disengaged so that the signal comes into operation, or remains engaged and prevents the disappearance or appearance of the signal. The persistency or the non-appearance 20 of the visual signal (at the end of the timing process) indicates the faulty setting of the fuse.

25 Two typical embodiments of the invention are illustrated by the accompanying drawings in which

30 Figs. 1 and 2 refer to the case where a signal becomes visible when the machine is empty, which signal, in certain circumstances, disappears when the projectile is inserted and reappears after the fuse has been timed, and in which Fig. 1 is a longitudinal sectional view of the machine and Fig. 35 2 is a cross-section of a portion thereof, and

35 Figs. 3 to 6 refer to the case where a signal becomes visible only when there is a correctly 40 timed projectile in the setting socket and disappears again when the projectile is removed, and in which these figures are sectional detail views.

45 A is the upper setting socket member the adjustment of which determines the time setting of the fuse, and B is the lower socket member which effects the time setting and which is provided with a spring pressed plunger having a setting nose b.

50 C denotes the driving member which is kept in continuous rotation. A coupling disc D is mounted on the hub of the socket member B so as to be capable of both rotation and axial displacement. When a projectile is inserted in the setting socket, the piston k is depressed by the weight of the 55 projectile, and by means of the pawl k₁ carries the

setting nose-securing ring S with it. The coupling disc D is disengaged in known manner, moves downwards, and causes the socket member B to be coupled with the driving member C. 5 When the timing operation is complete, the disc D rises again and is disengaged from the member C. Its axial movements are followed by a control ring E which is subjected to pressure by the springs f and is moved by the coupling disc D through the rods e, e₁. The said ring E on its downward and upward movement actuates a locking member v and also a visual signal member Z, a tongue z which rests on the control ring E and is pivoted about a spindle w being swung upwards and downwards, this swinging movement of the tongue z being communicated by way of the mechanism t, t₁ to the visual signal member Z.

The visual signal member Z is thus displaced 20 from view on the insertion of a projectile, and when the timing operation has been completed is swung back and again becomes visible. The device so far is already known.

Now, in order to cause the control of the visual signal to become dependent upon the depth of 25 the projectile in the setting socket, there is arranged in the lower socket member B a pawl b₁ adapted to be displaced transversely against the action of a spring f₁; the said pawl—as shown in 30 Fig. 2—engages on the one hand in a notch e₂ in the rod e₁ of the control ring E, and on the other hand by means of an inclined surface b₂ projecting in the path of the piston k co-operates with an inclined surface k₁ on the piston k. When 35 a projectile is placed sufficiently deeply into the setting socket, the piston k moves downwards and presses the pawl b₁ outwards against the influence of the spring f₁, whereby the pawl is pressed out of the notch e₂ in the rod e₁, and this 40 rod is disengaged. Not until this is it possible for the control ring E to move downwards and swing the visible signal member Z out of sight.

The pawl b₁ is disposed so low in the socket member B that the piston k does not release the pawl from the rod e₁ and so release the control ring E until it has moved into its lowest end 45 position.

In this position the adjusting noses of the 50 respective setting members (e.g. the spring loaded nose b of the lower socket member B) are at such a level in respect of the notches in the projectile and the timing ring that they are sure to engage in the notches and time the fuse correctly. If the projectile has not been inserted 55 into the setting socket to such a depth that this position of the piston k is obtained, the control ring E remains fixed and the visual signal member remains visible in the normal position. It does not disappear and that is an indication to 60 the gunner that the fuse has not been or is not timed. If, however, the projectile has been inserted correctly and, therefore, the fuse has been correctly timed, the control ring E, unchecked by the pawl b₁ which remains disengaged, will move 65 upwards with the coupling disc D, and the visual signal which has temporarily disappeared, reappears. The subsequent removal of the projectile from the socket and the consequent upward movement of the piston k allows the pawl b₁ to engage in the notch e₂ of the support e₁ and the 70 normal position is re-established.

The above-described manner of control of the visual signal demands a certain amount of care on the part of the person inserting the projectile 75 and/or the loading gunner, in order that the

non-occurrence of a temporary disappearance of the visual signal in the event of a projectile not being inserted sufficiently deeply, should not be overlooked and the signal which is visible taken to be a reappearance thereof after timing has taken place. 5

Such a possibility of error is precluded in the second example of construction according to Figs. 3-6, in which the visual signal is likewise actuated in dependence on the depth of 10 the projectile in the setting socket, but so that it appears only at the moment and so long as a projectile is correctly inserted in the setting socket. The visual signal disappears again when the projectile is removed from the setting 15 socket.

According to this form of construction (Figs. 3 and 4) between the spring loaded control ring (ring E of Fig. 1) and the coupling disc D there is inserted only one rod, namely a two-part rod 20 e₂. When the projectile has reached the correct depth in the setting socket, there is thrust transversely into the joint between the two parts and before the end of the timing operation a spring loaded bolt r so that the normally invisible signal, at the conclusion of the timing operation is swung into view by means of the control ring of the coupling disc D which rises again. This, however, does not occur when the projectile has not reached a sufficient depth in 30 the setting socket. The bolt r is arranged vertically displaceable in a horizontally displaceable plunger r₁, which is guided between vertical guides n₁ formed in a member n on the lower socket member B and which has a cylindrical shank r₂ which slides in a bush r₃ mounted in a cylindrical boring n₂ in the sleeve n. A vertical pin r₄ fixed firmly in the shank r₂ passes through longitudinal slots in the bush r₃ and projects into longitudinal recesses in the member n so that the bush r₃, when the plunger r₁ is held firm, is capable of longitudinal displacement in relation thereto, and the plunger r₁ is also capable of movement relatively to the member n. On the bush r₃ there is thrust a 35 second bush r₅ which is adapted to be turned in an enlarged portion n₃ of the boring n₂ of the member n. In the bush r₅ there is fixed a pin r₆ which on one side projects beyond the outer surface of the bush r₅ and is guided in an inclined slot r₇ of the bush r₅. A spring r₈ mounted inside the bush r₅ bears with one end against the pin r₆ and the other end on the end of the cylindrical shank r₂ of the plunger r₁. The outer end surface of the bush r₅ is provided with a 40 crank arm r₈ which by means of a crank pin r₉ projects into the forked head k₂ of a bolt k₃ fixed to the piston k, which bolt on the downward and upward movement of the piston k, that is on insertion and removal of a projectile, turns the bush r₅. The crank arm r₈ is provided with a projection r₉, Fig. 5. In the member n there is mounted on a spindle w carried therein at one end a latch w₁, which projects in the path of rotary movement of the projection r₉, and at the other end a lever w₂ (Fig. 6) which, in order to bolt the push bolt r, is disposed behind a notch in the pin r₄ and is held in position by means of a leaf spring w₃.

Where there is no projectile in the setting 70 socket and the piston k assumes its highest position in the setting socket, the bolt r is locked and lies in a withdrawn position at the side of the two-part rod e₂, as shown in Fig. 3. The control ring E (Fig. 1) has consequently under 75

the pressure of the spring f (Fig. 1) assumed its low position, in which the locking bolt v (Fig. 1) is released, the visual signal Z is swung downwards out of view. When a projectile is placed 5 in the setting socket and the plunger k sinks, the crank arm r_8 (Fig. 4) of the bush r_5 is carried along and the bush r_5 is turned. The bush r_3 is thereby displaced axially inwards by means of the inclined slot r_7 and the pin r_6 , the member 10 n engaging therewith, and the spring r_8' is loaded as the lever w_2 prevents axial motion.

After the projectile has been inserted, the coupling disc D moves downwards and the lower part of the two-part rod e_2 follows this movement leaving a gap between it and the upper part. Shortly before the plunger k has reached its lowest position, the projection r_9' of the crank arm r_8 comes into contact with the lever w located in its path and swings the lever w_2 out of 15 the notch in the pin r_4 . The plunger head r_1 is now released and is pressed outwards by the now expanding spring r_8' while at the same time the bolt r is thrust into the space between the individual members of the rod e_2 . This disengagement and effect of the bolt r , however, does not occur until the projectile has assumed such a depth in the setting socket that the engagement of the noses in the setting member in the notches in the fuse and the projectile and consequently the correct timing is ensured. When, 20 after the completion of the timing operation, the coupling disc D rises, as the rod e_2 in consequence of the interposition of the bolt r thrust between, is sufficiently long, the control ring E is also 25 raised and the visual signal Z swings into sight, thus indicating that the timing has been completed correctly. On the upward movement of the rod e_2 or the parts thereof, the bolt r is moved parallel to the axis of the projectile, that 30 is vertically in the plunger r_1 . A subsequent removal of the projectile from the setting socket and the consequent upward movement of the piston k allows the bush r_5 to turn backwards in the member n . The result is that the bush r_3 35 together with the plunger r_1 , the bolt r and the pin r_4 is withdrawn in the member n and the plunger r_1 is locked in this position by means of the lever w_2 . The returning bolt r frees the space between the parts of the rod e_2 and the control ring E (Fig. 1) is consequently lowered by the 40 action of its spring f , so that the visual signal Z disappears again from view and the initial state is obtained. Thus the visual signal appears only when the projectile has been correctly timed and 45 remains visible only as long as a correctly set projectile is in the setting socket.

If the projectile is not inserted sufficiently deep into the setting socket and, therefore, the bush r_5 is not turned sufficiently to cause 50 the projection r_9' to act on the lever w_2 , the bolt r remains in its locked or withdrawn position.

If then the coupling disc D is raised after the timing operation has been completed, although the lower part of the two-part rod e_2 55 is raised, it remains inoperative on the upper part as the intermediate member, the push bolt r not being added. The control ring E is, therefore, not raised and the display signal Z remains invisible in its downwardly swung position and its 60 absence indicates a faulty setting of the fuse.

It will be apparent that in place of the actuating member Z the mechanism described can easily be employed to actuate other indicating means,

for instance to open and close electric circuits, or to operate visual or acoustic signal devices.

I claim:—

1. A machine for setting projectile fuses comprising a projectile socket having upper and lower setting members capable of rotation relatively to each other, means on the lower socket member for engaging the fuse, drive means for the lower member, a coupling member movable upon insertion of a projectile into the socket to connect 10 the drive means to said lower member, an indicator, actuating connections between the coupling and the indicator, a device normally locking one of said connections, and means operated upon insertion of the projectile into the socket 15 to the proper depth for the fuse setting operation to render the locking device inoperative.

2. A machine for setting projectile fuses comprising a projectile socket having upper and lower setting members capable of rotation relatively to each other, means on the lower socket member for engaging the fuse, drive means for the lower member, a coupling member movable upon insertion of a projectile into the socket 20 to connect the drive means to said lower member, an indicator, means for actuating the indicator from the coupling member comprising a discontinuous normally inoperative transmission, and a member capable of being inserted into said discontinuous transmission to render it operative, 25 the insertion of said member being dependent on entrance of the projectile into the socket to the proper depth for the fuse setting operation.

3. A machine for setting projectile fuses comprising a projectile socket having upper and lower setting members capable of rotation relatively to each other, means on the lower socket member for engaging the fuse, drive means for the lower member, a coupling member movable upon insertion of a projectile into the socket to connect 30 the drive means to said lower member, an indicator, means for actuating the indicator in one direction against the action of a restoring spring, a rod through which said actuating means is moved by the coupling member, a lock normally 35 preventing movement of the rod, and a plunger movable in the fuse setting socket upon insertion of a projectile thereinto, said plunger when the projectile has entered the socket to the proper depth for the fuse setting operation operating the lock to release said rod.

4. A machine for setting projectile fuses comprising a projectile socket having upper and lower setting members capable of rotation relatively to each other, means on the lower socket member for engaging the fuse, drive means for the lower member, a coupling member movable upon insertion of a projectile into the socket to connect 40 the drive means to said lower member, an indicator, means for actuating the indicator in one direction against the action of a restoring spring, a rod through which said actuating means is moved by the coupling member, said rod being 45 two parts and the combined length of which is insufficient to form an operative transmission member, a sliding bolt normally withdrawn from said rod and adapted when projected between the parts thereof to render it an operative transmission member, and a lever actuated by entrance of the projectile into the socket to the proper 50 depth for the fuse setting operation, for so projecting the sliding bolt.

ANTON GIETMANN.
